FRAME FOR BUILDING OPENINGS

Charles P. Gifford, Chicago, Ill.

Application December 13, 1929
Serial No. 413,690

4 Claims. (Cl. 72—98)

The present invention relates to frames for building openings, and more in particular to a novel metallic frame construction adapted for use in building openings, such as doors, windows or the like.

Among the objects of the present invention are to provide a novel frame construction adapted to be inserted and anchored in a building opening, which construction eliminates the necessity of templet hardware for backing parts at the hinge and lock portions.

Another object is to provide a metallic buck with a channel for the reception of a jamb, said buck being constructed in sections so as to fit partitions or walls of varying size and thickness or depth.

A further object of the invention comprehends a frame construction which is substantially fire-proof and which is so constructed that a door or other closure may be hung therein in four different ways without any change in the frame.

Another object is to provide a metallic frame construction in which the buck is provided with a channel into which is mounted a jamb of wood, metal or fire-resisting material. A door or other closure may be connected to or hung from such jamb, the lock or latching means being attached to a like opposite jamb. Stops also may be connected to the jambs for stopping the door or closure in the proper plane. In structures having pre-formed stops, door or closure will generally swing back therefrom inasmuch as it is impracticable to always line up the frame parts. By the present construction of frame all errors and tolerances in constructing or erecting the frame relative to the partitions or walls will have no effect on the mounting of the door.

Further objects are to provide a construction of maximum simplicity, efficiency, economy and ease of assembly and detachment, and such further objects, advantages and capabilities as will later more fully appear and are inherently possessed thereby.

The invention further resides in the combination, construction and arrangements of parts illustrated in the accompanying drawing, and while I have shown therein a preferred embodiment, it is to be understood that the same is susceptible of modification and change, and comprehends other details, arrangements of parts, features and constructions, without departing from the spirit of my invention.

Referring to the drawing:

Fig. 1 is a view in front elevation of a door con-

struction made in accordance with the present invention.

Fig. 2 is an enlarged fragmentary view in horizontal cross section taken on the line 2—2 of Fig. 1.

Fig. 3 is a view similar to Fig. 2, but disclosing an alternate construction of buck and trim portions therefor.

Referring more particularly to Figs. 1 and 2 of the drawing, the embodiment selected to illustrate the invention is shown as comprising a metal buck 1, constructed in sections 2 and 3, having trim portions 4 and 5, respectively. These trim portions may be of any suitable design and configuration as desired, and extend from the opening to adjacent the plaster 6 of a partition 7. Such partition may be made up of tile 8 or the like as shown. A common backlining or backing block 9 of wood, fire-resisting material or the like, is mounted intermediate the trim portions and so formed as to interlock with flanges or extensions 10 and 11 of the sections 2 and 3. Inwardly extending portions 12 and 13 of the sections 2 and 3, are adapted to abut against the rear of the backlining and are attached thereto by nails, screws or the like 14.

Anchor members 15 are adapted to lie intermediate the tiling 8 and there be imbedded in or secured between such tiling. These anchor members on the outer end are provided with a threaded portion 16 adapted to pass through openings in the backlining. A washer 17 is positioned intermediate the tiling 8 and backlining 9, while a washer 18 and nut 19 are adapted to be mounted on the outer end of the threaded portion 16 and seat in an opening 20 in the face of the backlining.

Generally the sections of the buck and the backlining or backing block are assembled as a unit and shipped as such, altho if the size of the opening or the depth or thickness of the partition is not available, the sections may be shipped alone, and in view of the simplicity of the construction, a back lining may be readily formed and inserted intermediate the sections. This is a decided advantage over prior constructions wherein the metal buck is constructed integral and thus any variation in the size of the opening or depth or thickness of the partition, necessitated a different buck. Thus, in any such prior constructions, it was necessary to always have the exact dimensions of the building opening before manufacture could be started thereon. By the present construction, the metal trim may be standardized and formed or drawn in lengths of

any desired size. A stock of the same may always be kept on hand. This construction and method of manufacture, the trim portions generally being of identical form and design and 5 reversible, decreases considerably the cost of manufacture and installation, and further increases the efficiency of the same.

Within the channel formed by the sections of the buck and the backlining or backing block, is 10 fitted a jamb piece 21 of wood, metal, fire-resisting material or the like. This jamb is held tightly in position intermediate the sections 2 and 3 by reason of the flanges or extensions 10 and 11, and screws or the like 22 which pass through 15 hinges 23 and are further adapted to mount these hinges on the jamb.

A door or other closure 24 may be of any suitable construction, such as the disclosed compound key veneered door, and is hung or connected 20 to the jamb 21 by means of the hinges 23. A stop 25 is adapted to be attached to the jamb by any suitable securing means and may be secured to the jamb after the door has been hung and swung to the proper position. The jamb 25 on the opposite side of the opening is of the same construction and is provided with the necessary lock and corresponding stop, the stop being mounted in proper position so that the door will not have a back swing or wind. Any standard hardware may be used.

In Fig. 3 is disclosed an alternate construction of buck 1^a in which the sections 2^a are of slightly different contour. In this construction, the backlining or backing member 9^a is of slightly different contour, being provided with longitudinal grooves 26 adapted to intercept flanges 10^a and 11^a of the sections. Inwardly extending portions 12^a and 13^a of sections 2^a, are adapted to be connected by means of a plurality of channel straps or guide plates 27, spot 40 welded or otherwise connected thereto. These straps or guide plates are provided with inwardly bent portions 28, which become imbedded in the plaster 6, and provide a guiding means for the tile as clearly disclosed in Fig. 3. Anchor 45 members 29 having a horizontally extending portion 30 are adapted to seat between adjacent tiling, and a vertically extending portion 31 is adapted to seat intermediate the strap 27 and the rear of the backlining or backing member 9^a.

It will be readily seen from the above that the invention is simple in construction, can be readily assembled or disassembled, made to fit openings of any desired dimensions, and is extremely efficient. By this construction, the trim portions may be placed and anchored in position prior to the plastering and other interior finishing and 55 decorating. In prior constructions, where the bucks were made integral, upon a change in the depth or thickness of the partition or wall, new bucks

were necessary. In the present construction, the buck sections will accommodate various depths of openings, and when a change is made, it is only necessary to change the width of the backlining and jamb.

80

If further anchoring means are desired for affixing the jamb to the backlining or backing member, additional screws or other attaching means may be provided, principally under the stop members so that the attaching means will not be exposed. Although the construction has been shown in combination with a door, it will be readily seen that the same is adapted to be used for any other closure, such as a window or the like.

85

Having thus disclosed the invention, I claim:

90

1. A frame for building openings, comprising a metal buck having trim portions engaging the sides of a partition, said buck being formed in sections and providing a channel therebetween, a backlining and a jamb member in said channel, a member connecting said sections, and anchor means anchored between tiles of said partition and between the backlining and said connecting member, said connecting member being provided with extensions forming a guide for 100 the tiles of said partition.

95

2. A frame for building openings, comprising a metal buck formed with integral trim portions engaging the sides of a partition, said buck being constructed in sections and forming a channel of 105 any desired dimension therebetween, a backlining and a jamb member mounted in said channel, a plate bridging and connecting said sections, and anchor members for said buck anchored between tiles of said partition and said backlining and 110 plate.

105

3. A frame for building openings, comprising a metal buck having integral trim portions engaging the sides of a partition, said buck being constructed in sections and forming a channel of 115 any desired dimension therebetween, a backlining and a jamb member mounted in said channel, and a channel plate bridging and connecting said sections, the flanges of said channel plate being inwardly extended and forming a guiding means 120 for tile or the like in said partition.

115

4. A frame for building openings, comprising a metal buck constructed in sections and forming a channel therebetween, said sections being adapted to fit various size openings, each section 125 being formed with a trim portion and a portion of said channel, a backlining and a jamb in said channel to which a door or other closure may be attached, and a channel plate bridging and connecting said sections, the flanges of said channel plate being inwardly extended and providing a rearwardly opening guide for the tile or the like of the partition.
